PRONG FILE AND METHOD OF MAKING SAME

Filed Oct. 1, 1924

Inventor:
George A. Olsen,
Dyreforth, Lee, Christensen & Miles,
Attys.

UNITED STATES PATENT OFFICE.

GEORGE A. OLSEN, OF CHICAGO, ILLINOIS, ASSIGNOR TO ACCOUNTING DEVICES COMPANY, OF CHICAGO, ILLINOIS, A CORPORATION OF ILLINOIS.

PRONG FILE AND METHOD OF MAKING SAME.

Application filed October 1, 1924. Serial No. 741,077.

This invention relates to prong files and the like and to the method of making the same which is fully described in the following specification and shown in the accompanying drawing, in which:

Figure 1 is a top plan view of the back of a prong file embodying the invention;

Fig. 2 is a side elevation of one of the back sections before the end pieces and prongs are secured thereto;

Fig. 3 is a transverse section on the line 3 of Fig. 1; and

Fig. 4 is an enlarged partial perspective of the upset end of the prong.

The embodiment illustrated relates to prong files of the type shown and fully described in my Patent No. 1,500,630, and comprises the metal back for a prong file comprising two metal back sections 10 and 11 which are of L-shape as shown in Fig. 3, the ends being offset at 10^a and 11^a to accommodate the ears 12^a and 13^a of the end pieces 12 and 13, so that the outer surfaces of the ears 12^a and 13^a will lie substantially flush with the outer surfaces of the back sections 10 and 11. These end pieces are secured to the back sections by any suitable means such as spot welding at 14.

The end pieces 12 and 13 overlap and are hingedly secured together by means of rivets 15. The end pieces are made arcuate at 16. The radius of the arc being swung above the center of the post 17 onto which a locking arm 18 is pivoted. Fingers 12^b and 13^b are formed on these end pieces so as to provide notches at the junction on these fingers with the arcuate portions 16. A pin 19 is carried by the arm 18 and this is normally forced toward these notches by means of a spring 20 when therefore the back sections are swung toward each other, the pin 19 rides up over the finger 12^b and is pressed down into the notch by the spring 20, thereby blocking the two back sections in this closed position until it is released by pressing up on the pin 19.

Hinge plates 21 and 22 are secured to the back sections 12 and 13 by any suitable means such as spot welding (not shown), the upper edges of these sections having interrupted tubular portions 23 and 24 to which

the covers of the prong files may be hingedly mounted in a well known manner.

The arcuate prongs 25, the radius of whose arcs is swung from the centers of the rivets 15, are alternately secured to the back members 10 and 11 as shown in Fig. 1. As shown in Fig. 4, these prongs are upset and flattened at 26, thereby providing a suitable flat end which is adapted to lie flat against the inner face of the back members 10 and 11 so that it may be readily secured thereto by an electric weld or the like. A notch 27 is formed in this flattened face of the prong 25 and a complementary projection 28 is formed in the back member so that the prong can be readily positioned by placing the notch 27 over the projection 28. This projection is preferably pressed from the metal thereby leaving a corresponding depression 29 in the outside of the back member as shown in Fig. 3. The free ends of the prongs 25 are preferably round and fall in openings 30 in the opposite back member.

While I have shown and described but a single embodiment of this invention, it is to be understood that it is capable of many modifications. Changes therefore in the construction and arrangement may be made which do not depart from the spirit and scope of the invention as disclosed in the appended claims.

I claim:

1. In a prong file, two opposing back sections hingedly connected together, a prong secured to one section, said prong having a depression on the surface of the prong touching said section, and a complementary projection on the adjacent surface of said section for accurately centering said prong while it is being secured thereon.

2. In a prong file, two opposing back sections hingedly connected together, a prong secured to one section, said prong having a flattened end and a depression on the surface of the prong touching said section, and a complementary projection on the adjacent surface of said section for accurately centering said prong while it is being secured thereon.

3. In a prong file, two back sections hingedly secured together, a prong secured

to one section, said prong having a notch on the surface of said prong in contact with said section, and a complementary projection on the adjacent surface of said section for centering said prong, said prong being welded to said section.

4. In a prong file, two back sections hingedly secured together, a prong secured to one

section, said prong having one end upset and flattened, said flattened surface having a notch on the surface of said prong in contact with said section, and a complementary projection on the adjacent surface of said section for centering said prong, said prong being welded to said section.

GEORGE A. OLSEN.
